US0D1075810S

(12) **United States Design Patent** (10) Patent No.: **US D1,075,810 S**
(45) Date of Patent: ** May 20, 2025

(54) **DISPLAY SCREEN WITH GRAPHICAL USER INTERFACE OF A GAMING MACHINE**

(71) Applicant: **LNW Gaming, Inc.**, Las Vegas, NV (US)

(72) Inventor: **Sandra Chang-Adair**, Las Vegas, NV (US)

(73) Assignee: **LNW Gaming, Inc.**, Las Vegas, NV (US)

(**) Term: **15 Years**

(21) Appl. No.: **29/900,145**

(22) Filed: **Aug. 17, 2023**

(51) LOC (15) Cl. **14-04**

(52) U.S. Cl.

USPC **D14/485**

(57) **CLAIM**

The ornamental design for a display screen with graphical user interface of a gaming machine as shown and described.

DESCRIPTION

The FIGURE is a front view of a display screen with graphical user interface of a gaming machine showing our new design.

The peripheral broken line represents a display screen and a boundary and forms no part of the claimed design. The remaining broken lines show portions of the graphical user interface and form no part of the claimed design.
